NICHOLAS H. BORGFELDT AND FREDERICK W. RITTERHOFF, OF NEW YORK, N. Y.

Letters Patent No. 78,360, dated May 26, 1868.

MACHINE FOR GRANULATING AND FINISHING TOBACCO.

The Schedule referred to in these Letters Patent and making part of the same.

TO ALL WHOM IT MAY CONCERN:

Be it known that we, NICHOLAS H. BORGFELDT and FREDERICK W. RITTERHOFF, both of the city, county, and State of New York, have invented a new and improved Machine for Granulating and Finishing Tobacco; and we do hereby declare the following to be a full, clear, and exact description thereof, which will enable those skilled in the art to make and use the same, reference being had to the accompanying drawing, forming part of this specification, in which drawing—

Figure 1 represents a longitudinal vertical section of this invention.

Figure 2 is a transverse section thereof.

Similar letters indicate corresponding parts.

This invention relates to a machine which is intended particularly to facilitate the manufacture of killickinck and cigarette tobacco. The tobacco-scrap from which such tobacco is generally manufactured, are thrown into a hopper, which conducts the same to a cylindrical sieve surrounding a spiral brush, in such a manner that, by the action of the brush, a portion of the tobacco-scrap are broken up and forced through the sieve, while that portion of the scrap which is not broken up is carried out at the end of the sieve by the action of the spiral brush, said brush being so constructed that it bears on the tobacco-scrap with sufficient force to break the same up, while it is capable of yielding if it meets with a piece of wood or other hard substance mixed with the scrap, in such a manner that such hard substances are worked out at the end of the sieve, without causing any injury to said sieve. The fine particles of tobacco, and the dust mixed therewith, pass down into a second sieve containing a separating-screw, in such a manner that the dust is worked through said sieve, while the finished tobacco is worked out through a suitable discharge.

A represents a hopper, which leads to one end of a cylindrical sieve, B. The opposite end of this sieve is open, as shown in fig. 1, and in the interior of said sieve is placed a spiral brush, C, to which a revolving motion is imparted by hand or any other suitable power.

This brush is made of rattan, whalebone, wire, leather, or any other material of sufficient stiffness and elasticity, and the bristles are made of such a length that they sweep closely past the inner surface of the sieve. By the action of the brush the scrap of tobacco introduced through the hopper are worked along over the sieve, and a large portion of said scrap is broken and worked through the sieve, while the other unbroken portion of the scrap is worked out at the open end of the sieve, where the same is collected and again thrown into the hopper.

The advantage of our spiral brush over the unyielding rollers heretofore used in machines for granulating tobacco are twofold: firstly, the bristles of our brush, if they meet with a piece of wood or other hard substance, yield and push such hard substance along on the sieve, without producing any injury on the sieve, whereas, if an unyielding roller acts on such hard substance, the sieve is liable to become torn; secondly, by the action of our spiral brush the unbroken portion of the scrap is discharged at the end of the sieve automatically, and the operation of the machine can be continued without interruption. That portion of the tobacco-scrap which is broken up by the action of the spiral brush passes through the sieve B, down into the separating-sieve D, where it is acted on by the spiral flange E. The dust mixed with the tobacco is caused to drop down through the sieve D, and collects in the boxes F, while the finished tobacco is discharged through the aperture G, at the end of said sieve.

Having thus described our invention, what we claim as new, and desire to secure by Letters Patent, is—

In a device for granulating and finishing tobacco, the arrangement of the spiral brushes, cylindrical sieve B, conveyer-screw E, cylindrical sieve D, and the discharges F G, when constructed and operating as herein described.

This specification signed by us, this 20th day of March, 1868.

NICHOLAS H. BORGFELDT,
F. W. RITTERHOFF.
